UNITED STATES PATENT OFFICE.

JOHN J. W. KENAN, OF CRAFTON, PENNSYLVANIA.

FINISHING DEVICE.

Application filed February 9, 1927. Serial No. 166,858.

This invention relates to finishing devices and more in particular to devices for finishing the flat surfaces of parts made of wood, metal or other materials.

5 The primary object of this invention is to provide a finishing device which is adapted to successfully and economically replace finishing devices now in common use and in which the finishing means is a disc of sand-paper or 10 other similar abrasive. Another object of this invention is to provide such a device which is substantially self-cleaning, that is, a device wherein the removed portions of the material worked upon will not clog it up, thus 15 greatly impairing its efficiency. A further object of this invention is the provision of a finishing device composed of numerous renewable cutting-members which are so disposed as to remove parts of the material to be finished 20 by a gradual shearing action. Still another object is to provide a relatively simple finishing device which may be easily assembled or dismantled for repair and which will greatly outlast the type of devices of similar purpose 25 using discs of abrasive material. Additional features and advantages of this invention will appear from the following description considered in connection with the accompanying drawing forming a part of this application 30 and in which:

Fig. 1 is a front elevation of the preferred embodiment of my invention.

Fig. 2 is a sectional view through the device.

Fig. 3 is a fragmentary front elevation 35 showing a modified arrangement of my device.

Fig. 4 is also a fragmentary view showing another alternative construction.

Fig. 5 is a perspective view showing one of 40 the finishing elements used in Fig. 4.

Figs. 6 to 11 are front and side elevations showing a few of the cutting elements used in the constructions illustrated in Figs. 1 to 3.

Fig. 12 is a cross-section through two adjacent cutting elements of the type shown in Figs. 6 to 11, but with a spacer-strip inserted between said elements to increase the clearance.

Reference being had especially to Fig. 1, 50 my finishing device comprises a flat disc-member 1 having a downwardly directed peripheral flange 2 and a central hub 3 in which is the aperture 4 suitably tapped to accommodate the mandrel of a lathe (not shown) upon 55 which the disc-member is supported. The finishing of any material is effected by means

of a great number of cutting-blades, each having a beveled cutting edge 5, and which are assembled closely together so as to nearly cover the whole surface of the disc-member. 60 As shown in said Fig. 1, the cutting-blades are assembled in groups each comprising a major-blade 6 and the closely held minor-blades 7 which are all disposed in parallel relation to the major-blade. The latter extends from the periphery of the disc-member and is disposed tangentially to an imaginary circle concentric with the disc, thus forming an acute angle "A" with the radial line passing through the outer end of the blade. 70

The major and minor blades are held at the periphery of the disc-member by means of a clamping-ring 8 of substantially L-shaped cross-section, the vertical side 9 of which fits snugly on the flange 2 of the disc-member, whereas the shorter and horizontal side 10 is adapted to bear on the lugs 11 provided at the outer ends of said blades. Screws 21 are also shown for properly securing the clamping-ring on the disc-member. 80

The major-blade and some of the longer minor-blades are secured at their inner ends by means of the center-cap 12 comprising a hub 13 and the top-flange 14, the latter bearing on the lugs 15 cut at the inner ends of said blades. The center-cap is fastened on the disc-member by means of a screw 16 which engages a suitably threaded hole provided at the center of the disc-member. A dowel-pin 17 is also used to hold the center-cap in the proper position. On the hub 13 are cut the circumferential teeth 18 the purpose of which is to provide a support, or abutment, for the inner ends of the major-blades, whereby any slipping of the assembled cutting-blades on the disc-member is positively prevented. 90

The minor-blades which do not extend under the top-flange 14 need not, of course, have any lugs at the inner ends; the latter are cut straight and bear against the rearward side 100 of the preceding major-blade, see Figs. 1 and 3. One of such blades is shown in Figs. 10 and 11. These shorter blades are held together by means of pins 19, one or more of which are riveted to each blade and adapted to fit closely within elongated apertures 20 properly disposed in the next adjacent blade. These pin-connections, assisted by the pressure in the assembly of the blades will more than suffice to maintain the proper alignment 105 of the latter under all operating conditions. 110

In Fig. 3 I have shown a modified construc-

- tion which differs from the one just described only in that the major-blades 6 are disposed radially, instead of tangentially to an imaginary concentric circle. Apart from this structural difference, all the component elements of this finishing device are similar to the one shown in Figs. 1 and 2, especially, and for this reason they have been identified by the same reference number.
- 10 Figs. 4 and 5 illustrate a modification showing the use of tangentially disposed major cutting-edges. In this case each sector-like group 22 of cutting elements is machined out of a solid block, the minor cutting edges running all parallel to said major cutting edge. These cutting edges, on account of being parallel, may be easily milled out to the proper angle and under-cut to best suit the material to be finished. This type of structure may 20 be used preferably on the smaller sizes of finishing devices because of the difficulties encountered in hardening and grinding sectors of large dimensions. As shown in the drawing, these sectors may be fastened on the disc-member in the same manner as described for the built up groups of cutting elements.
- 25 When the nature of the material to be finished is such as to cause clogging of the cutting-blades, filler-strips 23 (see Fig. 12) may be inserted between the cutting-blades to increase the clearance required to permit of the free escape of the material removed.

30 Best results in finishing are obtained when the successive blades attack the material at an angle, thus effecting a gradual shearing action beginning at the outer end of each blade. This is best achieved by means of the tangentially disposed cutting-blades, since by this arrangement a gradual shearing action will result regardless of the relative position of the piece to be finished on the face of the device. On the other hand, if the radially disposed major cutting-blades 35 are used, gradual engagement of the latter with the object to be finished can only be procured by presenting said object at a point above or below the horizontal center-line of the finishing device. When presented directly on said center-line, the object will be attacked at one time by the whole length of the major-blade, as will be readily understood by referring to Fig. 3.

40 The most advantageous method of assembling a finishing device built as shown, for instance, in Fig. 1 is as follows: The major-blades 6 are first spaced evenly on the disc-member with the inner lugs abutting against the teeth 18 on the center-hub 13. The minor-blades are then successively laid in place, according to their decreasing lengths, until each sector-like space is filled with blades, due care being taken that none of the outer blade-ends protrude beyond the periphery of the disc-member. The clamp-

5 ing-ring 8 may now be placed about said disc-member and the screws 21 inserted. Finally, the center-cap is firmly screwed on, thus rigidly holding the cutting-blades on the disc-member.

60 To finish the flat surface of an object, the former is presented directly to the finishing device while rotating in the direction indicated by the arrows on the drawing and passed slowly across the face of the device, a suitable rest (not shown) being, of course, used to properly guide the object in a similar manner as employed, for instance, on wood turning lathes for guiding the turning-chisel.

65 Although my device is primarily intended for finishing machine parts or patterns made of wood, metal or other material, it may also be used to great advantage in combination with floor-finishing machines or on any other kinds of work where surfaces have heretofore been finished with sand-paper or analogous abrasives.

70 Many changes in the precise construction, arrangement and combination of the various parts may be made without exceeding the scope of the claims, and I reserve the right to make all such changes as may be thought desirable.

75 I claim:

1. In a finishing device of the character described, a plane rotatable disc-member; a plurality of straight removable cutting-blades positioned on said disc-member and arranged in groups, each group comprising a straight major blade and a plurality of straight minor blades disposed in parallel relation to said major blade, each of said major and minor blades having at its outer end a lug; a clamping ring of substantially L-shaped cross-section fitting about said disc-member and adapted to engage simultaneously said lugs, and a cap positioned centrally on said disc-member adapted to engage the inner ends of said major blades and of some of said minor blades.

80 2. In a finishing device of the character described, a plane rotatable disc-member; a plurality of removable cutting-blades positioned on said disc-member and arranged in groups, each group comprising a straight major blade and a plurality of straight minor blades disposed in parallel relation to said major blade; a lug positioned at the outer end of each major and minor blade; a clamping-ring of substantially L-shaped cross-section fitting about said disc-member and adapted to engage simultaneously said lugs; and a cap positioned centrally on said disc-member adapted to engage the inner ends of said major blades and of some of said minor blades; said major blades being disposed tangentially to an imaginary circle concentric with the disc-member, for the purpose set forth.

3. In a finishing device of the character described, a plane rotatable disc-member; a plurality of removable cutting-blades positioned on said disc-member and arranged in groups, each group comprising a straight major blade and a plurality of straight minor blades disposed in parallel relation to said major blade; a lug positioned at the outer end of each major and minor blade; a clamping-ring of substantially L-shaped cross-section fitting about said disc-member and adapted to engage simultaneously said lugs; a cap positioned centrally on said disc-member adapted to engage the inner ends of said major blades and of some of said minor blades, and teeth disposed circumferentially on said cap to serve as abutments for the inner ends of said major blades.

4. In a finishing device of the character described, a plane rotatable disc-member; a plurality of removable cutting-blades positioned on said disc-member and arranged in groups, each group comprising a straight major blade and a plurality of straight minor blades disposed in parallel relation to said major blade; a lug positioned at the outer end of each major blade and minor blade; a lug positioned at the inner end of each major blade and of some of the minor blades; a clamping-ring of substantially L-shaped cross-section secured about said disc-member and adapted to engage simultaneously the lugs at the outer ends of said blades, and a cap positioned centrally on said disc-member and comprising a hub and a top-flange adapted to clamp the lugs on the inner ends of the major blades and on some of the minor blades.

5. In a finishing device of the character described, a plane rotatable disc-member; a plurality of removable cutting-blades positioned on said disc-member and arranged in groups, each group comprising a straight major blade and a plurality of straight minor blades disposed in parallel relation to said major blade; a lug positioned at the outer end of each major blade and minor blade; a lug positioned at the inner end of each major blade and of some of the minor blades, a clamping-ring of substantially L-shaped cross-section secured about said disc-member and adapted to engage simultaneously the lugs at the outer ends of said blades, a cap positioned centrally on said disc-member and comprising a hub and a top flange adapted to clamp the lugs on the inner ends of the major blades and on some of the minor blades,

and teeth disposed circumferentially on said hub to serve as abutments for the inner ends of said major-blades.

6. In a finishing device of the character described, a plane rotatable disc-member; a plurality of removable cutting-blades positioned on said disc-member and arranged in groups; each group comprising a straight major blade and a plurality of straight minor blades disposed in parallel relation to said major blade; a lug positioned at the outer end of each major blade and minor blade; a lug positioned at the inner end of each major blade and of some of the minor blades; a clamping-ring of substantially L-shaped cross-section secured about said disc-member and adapted to engage simultaneously the lugs at the outer ends of said blades; a cap positioned centrally on said disc-member and comprising a hub and a top-flange adapted to clamp the lugs on the inner ends of the major blades and on some of the minor blades; teeth disposed circumferentially on said hub to serve as abutments for the inner ends of said major-blades, and means for securing together the ends of the minor blades not secured by said central cap.

7. In a finishing device of the character described, a plane rotatable disc-member; a plurality of removable cutting-blades positioned on said disc-member and arranged in groups, each group comprising a straight major blade and a plurality of straight minor blades disposed in parallel relation to said major blade; a lug positioned at the outer end of each major blade and minor blade; a lug positioned at the inner end of each major blade and of some of the minor blades; a clamping-ring of substantially L-shaped cross-section secured about said disc-member and adapted to engage simultaneously the lugs at the outer ends of said blades; a cap positioned centrally on said disc-member and comprising a hub and a top-flange adapted to clamp the lugs on the inner ends of the major blades and on some of the minor blades; teeth disposed circumferentially on said hub to serve as abutments for the inner ends of said major-blades, and means for securing together the ends of the minor blades not secured by said central cap, said means consisting of pins secured to said minor blades adapted to engage slots positioned in the next adjacent blades.

In testimony whereof I affix my signature.
JOHN J. W. KENAN.
